UNITED STATES PATENT OFFICE.

MOSES C. HARGRAVE, OF WILMINGTON, NORTH CAROLINA.

SASH-HOLDER.

SPECIFICATION forming part of Letters Patent No. 345,050, dated July 6, 1886.

Application filed December 24, 1885. Serial No. 186,654. (No model.)

To all whom it may concern:

Be it known that I, MOSES C. HARGRAVE, of 5
Wilmington, in the county of New Hanover
and State of North Carolina, have invented a
new and useful Improvement in Sash-Holders,
of which the following is a description.

Referring to the accompanying drawings,
Figure 1 is a perspective view showing my de-
vice in place in a part of a window-casing.
10 Fig. 2 is a perspective view of the device re-
moved, part of its case being broken away to
show the inner parts. Fig. 3 is a front view
of the device. Fig. 4 is a side elevation of the
carrier, the side being partially broken away
15 to show the working parts, and Fig. 5 is a side
elevation of the device with dotted lines to
show parts when positions are changed.

The invention relates to that class of sash-
holders in which spring-actuated pulleys are
20 employed to bear against the edge of the sash
as a substitute for the cords and weights.

The invention has for an object to combine
with said pressure-pulleys a lock which can be
conveniently manipulated to secure the sash,
25 and to arrange such lock in the immediate car-
rier of the pulleys in such manner as to pre-
sent no obstruction to the working thereof
when the sash is unlocked.

It has for further objects other improve-
30 ments, as will be explained.

The invention consists in certain novel con-
structions and combinations of parts, as will
be hereinafter described.

The outer or main case A is formed some-
35 what similar to the cases now commonly used
for the guide-pulleys used in connection with
balance-weights. In the sides of this case A,
I form parallel slots a and a curved or seg-
mental slot, B. I also provide the case with
40 a series of holes, C, for the purposes hereinafter
explained. The carrier D is fitted and
movable within the case A, and is provided
with pins or studs d, which extend through the
slots a, and serve to guide the movement of
45 the carrier as well as to limit the extent of
such movement. These studs d are prefera-
bly the extended ends of the axles of rollers
E, the peripheries of which project beyond
the face of the carrier and the case. A spring,
50 F, is connected with the case and bears against
the inner side of the carrier, giving the latter

an outward tension. This spring is prefera-
bly, as shown in the present instance, a curved
bar-spring having its ends bearing against the
inner side of the carrier at the ends thereof,
for which purpose the carrier is formed solid
55 for a considerable distance from its ends to
form bearings for the spring. At its middle
portion the spring is provided with ears f, pro-
jected rearwardly from its opposite sides, and
having openings for the bolt G, which is passed
60 through one opening C in the casing A,
thence through openings f and the opposite
opening C, securing the spring to the case.
By adjusting the bolt into different pairs of
65 openings C the spring may be caused to bear
with greater or less tension on the carrier, and
when the spring by use in one position has
become partially relaxed or weakened, the bolt
may be adjusted nearer to the carrier.

In operation the pulleys bearing against the
edge of the sash by the pressure so exerted
will hold the sash in any position to which it
may be adjusted and yet permit it to be easily
moved up or down, as desired. The carrier
75 is also provided with a lock, H, by which to
fasten the sash. This lock is substantially a
lever pivoted between its ends midway the
rollers E, and having a head, I, at one end and
a handle, J, at the opposite end. The head I
80 has a curved bearing-face, i, usually serrated,
as shown, and such face is curved eccentric-
ally to the pivot of the lock. At or near its
extremity the handle J is provided with a lat-
eral stem, which projects through the slot B.
85 By this stem the lock may be adjusted into
and out of engagement with the sash. When
adjusted completely out of engagement with
the sash, the lock will lie below the bearing-
line of the rollers. When turned outward, the
90 head I will engage the edge of the sash, and
any effort to move the sash will only bind the
lock more firmly thereagainst. The slot B,
through which the stem j passes, is made suffi-
ciently wide to permit the lateral movement
95 of such stem in the movements of the carrier.
At its end b, which, for convenience of refer-
ence I term its "rear end," the slot is extend-
ed to permit the inward movement of the stem
when the head is pressed against the sash.

In order to prevent the lock-handle from
striking the roller when such lock is adjusted

out of engagement with the sash, I employ the stop-plate L, which projects partly over the inner face of the roller, as shown. This plate is preferably provided with an extension, l, fitting around a cross-pin, M, and is supported on the crown of a bail or staple, N, the arms n of which are supported on the pivotal pin of the lever-lock.

In the use of my invention the case and contents are placed in the sash-channel of the window-case at a point at or nearly opposite the meeting-rail of the sash, and the stem of the lever handle extends into the room through a slot, K, formed in the window-easing, said slot being curved concentrically with slot a to permit the movement of the stem necessary to adjust the lock into and out of engagement with the sash.

It is usual to employ two holders with each sash; but only one of such holders is provided with a lock.

The invention is much easier applied than the pulley and weight commonly used, can be used with any ordinary window-frame, and, in addition to supporting the sash at any desired point, prevents all rattling of the sash in the frame.

Having thus described my invention, what I claim as new, is—

1. In a sash-holder, the combination of a carrier provided with rollers, a spring supporting said carrier, and a lever-lock adjustable into engagement with the sash and supported in the carrier, whereby when the lock

is engaged with the sash the rollers will be held clear thereof, substantially as set forth.

2. A sash-holder comprising a carrier, rollers therein, a lever-lock, a stop-plate, L, having an extension, l, a bail or staple, N, and a spring engaging the carrier, substantially as set forth. 40

3. In a sash-holder, the combination of the case having a series of holes, C, the carrier, the bar-spring having its ends engaging said carrier, and the bolt connected centrally with said spring and adjustable into any desired pair of 45 holes C, substantially as set forth.

4. In a sash-holder, the combination of the casing having a curved slot, b, the spring-actuated carrier provided with rollers, and the lever-lock having a curved head, I, and handle J, and a stem, j, connected with said handle and projecting through the slot B, substantially as set forth. 50

5. The improved sash-holder consisting of the casing having curved slot B and parallel slots a, and provided with a series of holes, C, the carrier having bearing-rollers and provided with lateral studs projected into slots a, the lever-lock having a head, I, curved at i eccentrically to its pivot, and provided with a handle, J, the stem j, extended from said handle through slot B, the stop-plate L, and the support N therefor, all arranged and operating substantially as set forth. 55 60

MOSES C. HARGRAVE.
